(57) **CLAIM**

The ornamental design for a baffle with closed ends, as shown and described.

DESCRIPTION

FIG. 1 is a top left front perspective view of a baffle with closed ends including my design;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof;
FIG. 7 is a bottom plan view thereof;
FIG. 8 is a top left front prospective view of an alternative embodiment of the baffle with closed ends in which portions are wrapped in felted polyethylene terephthalate (PET);
FIG. 9 is a front elevation view thereof;
FIG. 10 is a rear elevation view thereof;
FIG. 11 is a left elevation view thereof;
FIG. 12 is a right elevation view thereof;
FIG. 13 is a top plan view thereof; and,
FIG. 14 is a bottom plan view thereof.

Portions of the claims design are shown separated and bound by a bracket to indicate indeterminate length.

The baffle with closed ends is shown with a symbolic break in its length. The appearance of any portion of the article between the break lines form no part of the claimed design.
